UNITED STATES PATENT OFFICE.

EWALD F. PAWSAT AND HERMANN PAWSAT, OF SHEBOYGAN, WISCONSIN.

GRIPPER ATTACHMENT FOR PEDALS.

959,160.

Specification of Letters Patent. Patented May 24, 1910.

Application filed January 17, 1910. Serial No. 538,413.

To all whom it may concern:

Be it known that we, EWALD F. PAWSAT and HERMANN PAWSAT, citizens of the United States, and residents of Sheboygan, 5 in the county of Sheboygan and State of Wisconsin, have invented certain new and useful Improvements in Gripper Attachments for Pedals; and we do hereby declare that the following is a full, clear, and exact 10 description thereof.

The object of our invention is to provide a simple and effective gripping-plate attachment for bicycle pedals, the invention consisting in certain peculiarities of construction 15 and combination of parts as fully set forth hereinafter with reference to the accompanying drawings and subsequently claimed.

In the drawings Figure 1 represents a side elevation of a pedal provided with a gripping-plate embodying the features of our 20 invention, parts of the same being broken away and in section to better illustrate its details of construction; Fig. 2, a transverse sectional view of the same as indicated by 25 line 2—2 of Fig. 1, and Fig. 3, an inverted plan view of the same.

Referring by characters to the drawings, 1 indicates a pedal pin upon which is loosely mounted the sleeve portion 2 of the pedal. 20 The sleeve is provided with laterally extending arms 3 for the support of a stirrup-strap 4, the same being of the rat-trap type and provided with upper and lower toothed edges cut away in scroll formation for the 35 purpose of ornamentation and reduction in weight. This pedal is of standard type and forms no part of our invention, which invention primarily consists in providing means for attaching a corrugated gripping-plate to 40 said pedal, the gripping-plate being adjusted over the toothed edges of the stirrup-strap with its corrugated surface exposed for the purpose of being engaged by the feet of the operator whereby liability of slipping is 45 eliminated. The corrugated gripping surface is preferably composed of some pliable material such as rubber or analogous material reinforced by a metallic backing-plate.

Referring to the three figures of the drawings, 5 indicates a flat metallic backing-plate, which plate bridges the space intermediate of the edges of the stirrup-strap 4 with its 50 lower face arranged to rest upon the toothed edge of the same. The width of the tread portion of the backing-plate is the same as

the width between the opposite edges of the stirrup-strap, the said tread portion being terminated with an abrupt right angle flange 6, which flange is bent downwardly and overlaps the outer opposite faces of the stirrup-strap. Ears 7 extend downwardly from the central portion of the flanges, the ears being formed with elongated slots 8, which slots are arranged to coincide with apertures 9 forming part of the scroll design of the stirrup-strap. The ears 7 with their elongated slots, together with the apertures 9 in the scroll design of the stirrup-strap thus form a convenient and simple means whereby the gripping-plate may be securely and quickly 60 attached to a pedal of standard design. A single bolt 10 is utilized for securing these parts together, which bolt is provided with an intermediate offset portion 11 whereby said bolt when adjusted to position is cleared 65 from the sleeve portion 2 of the pedal. The offset portion 11 is parallel to the head and shank portion of the bolt, being connected thereto by oblique bolt sections 12 as best shown in Fig. 2. Owing to the fact that the 70 sections 12 are disposed obliquely with relation to the remainder of the bolt the same may readily be inserted through the respective elongated slots of the ears 7 and apertures 9 of the stirrup-strap, the peculiar 75 formation rendering it possible to pass said bolts through these various slots and apertures and over the sleeve 2.

One end of the bolt 10 is threaded for the 80 reception of a nut 13 and after insertion of 85 the bolt in its position thereon said nut is run upon the screw threaded end to securely bind the parts together.

By referring to Fig. 2 of the drawing it 90 will be seen that when the bolt and various 95 parts are assembled the offset portion 11 of said bolt passes between the gripping-plate and the sleeve 2 and thus renders the device slightly as well as to insure the bolt 100 being retained in position even though the clamping nut should become detached. This is due to the fact that when the user exerts pressure upon the gripping-plate, the latter is sufficiently resilient to permit a slight sag, whereby the offset portion 11 of the bolt is 105 gripped between said gripping-plate and sleeve.

A sheet 14, preferably of corrugated rubber, is secured to the tread portion of the 110 backing-strip 5 by means of rivets 15, the

corrugations of the rubber sheet being disposed longitudinally of the pedal, whereby gripping efficiency is obtained.

We are aware that gripping devices of this character have been utilized heretofore in connection with backing-plates, but in these instances such backing-plates have been provided with longitudinal grooves or flanges at their edges, between which the corrugated 5 rubber sheet is inserted, but this construction requires great accuracy in the dimensions of the sheet in order that it may be fitted upon the backing-strip and, furthermore, in practice it has been found that by 10 grooving or flanging the backing-strip the number of operations for completing the device is increased, thus proportionately increasing the cost in manufacture and at the same time these grooves or flanges tend to 15 crystallize the metal and thereby weaken the strength of the same to the detriment of its wearing qualities. By simply utilizing a flat, unbroken surface for the tread portion of the backing-strip in connection with a 20 single longitudinal bend at its edges as shown, the above objectionable features of construction have thus been eliminated.

We claim:

1. In a bicycle pedal having a scroll stirrup-strap; the combination of a gripping attachment comprising a continuous backing-plate having an unbroken flat tread portion, right angle flanged portions extending from the backing-plate and adapted to overlap the stirrup-strap, slotted ears extending from the flanges, the slots being arranged to coincide with apertures of the scrolled stirrup-strap, and a securing bolt for the gripping attachment, the securing bolt being 30 arranged to pass through the slotted apertures of the ears and scroll apertures of the 35 stirrup-strap aforesaid.

2. In a bicycle pedal having a scroll stirrup-strap; the combination of a gripping attachment comprising a continuous backing-plate having an unbroken tread portion, right angle flanges extending from the backing-plate adapted to overlap the stirrup-strap, slotted ears extending from the flanges and means for securing the slotted 45 ears to said stirrup-strap.

3. In a bicycle pedal having a scroll stirrup-strap; the combination of a gripping attachment comprising a backing-plate having apertured flanged extensions adapted to 50 engage the stirrup-strap, a corrugated sheet secured to the backing-plate and a securing bolt for the backing-plate, the securing bolt being provided with an intermediate offset portion.

4. In a bicycle pedal having a central sleeve and apertured stirrup-strap; a gripping attachment for the pedal comprising a backing-strip having apertured flanges adapted to straddle the stirrup-strap, a corrugated sheet secured to the backing-plate and a securing bolt for the gripping attachment arranged to pass through the flanged apertures and stirrup apertures, the bolt being provided with an intermediate offset portion 55 disposed to one side of the pedal sleeve, the offset portion being connected by oblique sections to the head and shank portions of said bolt.

In testimony that we claim the foregoing 75 we have hereunto set our hands at Sheboygan in the county of Sheboygan and State of Wisconsin in the presence of two witnesses.

EWALD F. PAWSAT.
HERMANN PAWSAT.
